[57] CLAIM

The ornamental design for a combined card file, adhesive note dispenser and desk caddy, as shown and described.

DESCRIPTION

FIG. 1 is a top, left front perspective view of a combined card file, adhesive note dispenser and desk caddy showing my new design;

FIG. 2 is a top plan view drawn to an enlarged scale;

FIG. 3 is a front elevational view of FIG. 2;

FIG. 4 is a right side elevational view of FIG. 2, the left side being a mirror image thereof;

FIG. 5 is a rear elevational view of FIG. 2;

FIG. 6 is a bottom plan view of FIG. 2; and,

FIG. 7 is a top, left front perspective view on a reduced scale, the note paper sheet and file cards being depicted by means of broken lines for illustrative purposes only and forming no part of the claimed design.
